DESCRIPTION

FIG. 1 is a perspective view of a first embodiment of an electronic device with stand;

FIG. 2 is a front elevation view thereof;

FIG. 3 is a back elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a perspective view of a second embodiment of an electronic device with stand;

FIG. 9 is a front elevation view thereof;

FIG. 10 is a back elevation view thereof;

FIG. 11 is a left side elevation view thereof;

FIG. 12 is a right side elevation view thereof;

FIG. 13 is a top plan view thereof;

FIG. 14 is a bottom plan view thereof;

FIG. 15 is another perspective view of the electron device with stand show in FIG. 1 with the adjustable tilts shown in an alternate position;

FIG. 16 is a back elevation view thereof; and,

FIG. 17 is a back elevation view of the electronic device with stand shown in FIGS. 1 and 15 with the adjustable tilts shown in an alternate position.

(Continued)

The broken lines in FIGS. 1-17 illustrate portions of the electronic device with stand that form no part thereof.
